UNITED STATES PATENT OFFICE.

HAZEL H. WALTZ, OF OAKLAND, CALIFORNIA.

HAIRPIN.

Application filed June 24, 1925. Serial No. 39,219.

To all whom it may concern:

Be it known that I, HAZEL H. WALTZ, a citizen of the United States, residing at Oakland, in the county of Alameda and State of California, have invented certain new and useful Improvements in Hairpins, of which the following is a specification.

My invention relates to hair pins in general, and more particularly to the type of hair pin adapted to engage the hair between a pair of contacting members.

It is well known that the common type of hair pin is prone to dislodge and slip out from the hair upon unexpected occasions, and which occurrences necessitates the use of many pins for the holding of the dressed hair in place to assure that some will remain and function. Also with bobbed hair in vogue it is difficult to keep the front-side hair from the eyes by the present pins because of their insecure hold to the short hair at the ears. Therefore, with the end in view of overcoming the above deficiencies, I have designed a pin which can be relied upon to hold the hair firmly in place and where desired and with a minimum number of pins, one on each side of the head being sufficient to hold the hair from the eyes.

Some women have but little hair and they find it very difficult to secure false hair thereto with any degree of assurance that the same will remain fixed by the present means of attachment, which generally is to bend and twist ordinary hair pins about the anchoring strands of hair, so a further object of my invention is to meet the problems attendant with those who have but little hair and with those who have thin hair.

As a hairdress by profession I have encountered the multitude of hair problems facing the hairdresser, and as a solution to the problems I have provided a hair pin of a design and structure that will efficiently accomplish the retention to the head of hair, whether it be thickly or thinly covered, with such attachments as bobs, swirls, curls, puffs, waves, braids, clusters, side pieces, ear muffs, switches and all weft attachments, also flowers and other hair decorations, and by the same pin means hold the natural hair where and in the form desired.

Other objects and advantages and the features of construction of the invention, will appear in the subjoined description of the accompanying sheet of drawings in which:

Figure 1 is an edge view of a hair pin

constructed in accordance with my invention, and Figure 2 is a face view of the same.

Figures 3 and 4 are views similar to Figure 1 but with the free ends of the pin rounded differently; and

Figure 5 is also an edge view similar to Figure 1 but with the pin legs of equal length.

Adverting to the various figures of the drawing I will now describe the invention in detail: For the purpose of clarity I have enlarged all the figures to bring out the features of the improvement. The letter S designates a single strip of material such as spring steel, spring brass or other suitable material having resilient properties, and is of a broad width W compared to its thickness T. The strip is bent over about midway of its length to form legs 6 and 7 joined by a bend 8.

The resultant structure is a pin having a pair of legs substantially the length of the structure and terminating in free ends 9 and 10 and a slender loop 11. By the resilient material formed as shown, the legs will be constantly urged toward one another, thus effecting a contact pressure throughout their length. The legs are straight and parallel, and one of them is slightly longer than the other to effect a parting of the legs with ease by the finger nail when it is desired to put the pin into use. The ends are also slightly rounded as an aid in the insertion of the pin through the hair, stem ends, wefts, etc. It is to be observed that the free ends do not flare outwardly as I have found such a construction unsatisfactory in insertion and engagement purposes and also they have a tendency to scratch the scalp.

In operation, the hair attachment selected is placed upon the head and on or in the hair where desired, and by inserting the forced-apart mouth of the pin into and over strands of natural and unnatural hair, or into stem ends or through the meshes of wefts in combination with natural hair strands a resilient holding and locking engagement is effected by the urging of the pin legs to press against each other. In wefts one pin at each end is sufficient and for a large head of hair one in the middle is advisable. For weft attachments and in the old way of securing them to the average head of hair, I have used as many as ten or twelve ordinary pins, but with my improved pin in use two will suffice. From this it is obvious another

great advantage is gained, namely, the visibility of pins is reduced to a minimum. And a still further advantage gained is that one may bend over or the head may be shaken 5 with practically no danger of the false hair attachments being dislodged or shaken off due to the long area of binding surface of my improved pin which effects the holding engagement.

10 From the foregoing description taken in connection with the accompanying drawings, the advantages of the construction and method of operation will be readily understood by those skilled in the art to which 15 the invention appertains, and while I have described the principle of operation, together with the device which I now consider to be the best embodiment thereof, I desire to have it understood that the device shown 20 is merely illustrative and that such changes may be made, when desired, as fall within the scope of the appended claims.

Having thus described my invention, what

I claim as new and desire to secure by Letters Patent of the United States is the following:

1. A hair pin made of spring material having greater width than thickness, consisting of two opposed legs, each leg of said pin having parallel side edges and a connecting bend, the said legs being of the same width and in contact with each other at their free ends and for the major length of the pin.

2. A hair pin consisting of two opposed legs, made of spring material having greater width than thickness, each leg of said pin having parallel side edges and a connecting bend, the said legs being of the same width and in contact with each other at their free ends and for the major length of the pin, and one of said legs being longer than the other.

In testimony whereof I affix my signature.

HAZEL H. WALTZ.
